(57) **CLAIM**

The ornamental design for an extraction container assembly for specimen detection, as shown and described.

DESCRIPTION

FIG. 1 is a perspective view of an extraction container assembly for specimen detection showing my new design; FIG. 2 is a front elevational view thereof; FIG. 3 is a rear elevational view thereof; FIG. 4 is an enlarged top plan view thereof; FIG. 5 is an enlarged bottom plan view thereof; FIG. 6 is a left side elevational view thereof; FIG. 7 is a right-side elevational view thereof; and, FIG. 8 is an exploded perspective view thereof, where the nozzle is shown separate from the remainder of the extraction container assembly for specimen detection.

The masked areas adjacent to the broken lines in FIGS. 1, 4, and 8 form no part of the claimed design. The broken lines define the bounds of the claimed design and form no part thereof.
